HAND OPERATED LOOM

David C. Churchill, Berea, Ky.

Application December 20, 1935, Serial No. 55,359

4 Claims. (Cl. 139—29)

This invention relates to textile looms of the hand-operated type.

Heretofore, textile looms have generally been of such size and weight and cost as to prohibit their general introduction into individual homes or their extensive use in schools, et cetera. Textile weaving thus has never been available in the home as "pick-up" work as have knitting, crocheting, et cetera, and even in schools and other institutions where weaving is sometimes taught there is seldom if ever a loom available for each pupil.

Furthermore, even the simplest of manually operated looms have heretofore required the laying of the warp threads upon the beams of the loom before weaving can be begun or a change made from one kind of work to another, and this tedious time-consuming operation has heretofore discouraged those who otherwise might become interested and ultimately skilled in weaving.

It is therefore one of the main objects of this invention to provide a practical loom which can be constructed so cheaply and which may be so small in size and light in weight and simple to operate as to overcome the above mentioned objections to prior looms, and to make weaving so attractive and simple that it will be practiced by the individual as generally as crocheting, knitting, et cetera, in the home, school, et cetera.

Other objects of the invention are:

To provide a loom having improved construction whereby work which has been set up in the loom and started may be removed intact without damage thereto, together with the warp supply, at any time, and other work and warp substituted therefor quickly and conveniently;

To provide a loom of the "refill" type in which the warp and the beater reed and heddles may be removed as an assembled unit and another warp and beater reed and heddle assembly set thereinto ready for work;

To provide an improved construction of reed and heddle and warp elements which may be manufactured and sold assembled together as a unit, and which may be quickly and conveniently set into a loom in condition ready for weaving or quickly and conveniently removed as a unit from the loom;

To provide for looms an improved shedding mechanism;

To provide an improved beating mechanism;

To provide an improved warp beam construction;

To provide a warp beam having an improved let-out mechanism;

To provide an improved cloth or work beam construction;

To provide a cloth beam having an improved take-up mechanism;

To provide an improved reed mechanism;

To provide an improved reed mounting mechanism;

To provide generally an improved manually operated loom construction;

To provide a textile loom which may be operated and adjusted entirely without the use of tools or other accessory devices.

Other objects will be apparent to those skilled in the art to which my invention appertains.

My invention is fully disclosed in the following description taken in connection with the accompanying drawings, in which:

Fig. 1 is a side elevational view, with parts broken away for clearness, of a loom embodying my invention;

Fig. 2 is a view similar to Fig. 1 taken from the opposite side thereof with parts broken away for clearness;

Fig. 3 is a cross-sectional view taken approximately from the plane 3—3 of Fig. 1;

Fig. 4 is a cross-sectional view taken approximately from the plane 4—4 of Fig. 1;

Fig. 5 is a fragmentary view similar to a part of Fig. 1 illustrating parts thereof in different positions; and the view may be considered as taken from the plane 5—5 of Fig. 6;

Fig. 6 is a view of the parts of Fig. 5, the view being taken in the direction of the arrow 6 of Fig. 5;

Fig. 7 is a view similar to Fig. 5 with the parts thereof in a still different position;

Fig. 8 is a view taken approximately from the direction of the arrow 8 of Fig. 7;

Fig. 9 is a view of certain parts shown in Figs. 1, 5 and 7, drawn substantially to the preferred full scale and with the parts in different operative positions;

Fig. 10 is a fragmentary view of a part of a lease reed which I may employ, the view being taken substantially from the same direction as Figs. 6 and 8;

Fig. 11 is a side elevational view showing separately some of the elements of the other figures and constituting a "refill" unit which I may employ;

Fig. 12 is a top plan view of the parts of Fig. 11;

Fig. 13 is a fragmentary sectional view taken from the plane 13—13 of Fig. 1;

Fig. 14 is a fragmentary elevational view taken from the direction of the arrow 14 of Fig. 3;

Fig. 15 is a fragmentary sectional view taken from the plane 15—15 of Fig. 1;

5 Figs. 16 and 17 are views similar to Figs. 11 and 12, but illustrating another form which the "refill" unit may have, and drawn to a smaller scale.

Referring to the drawings, I have shown generally at 1 a main frame upon which the parts of the loom are mounted, comprising a base 2 and a pair of spaced side rails 3 and 4. A cloth beam 5 to be more fully described is rotatably mounted on the rails 3 and 4 at one end of the base and a warp beam 6 is mounted at the other end. Warp threads 7 wound in a supply several layers deep on the beam 6 at one end are wound at their other ends on the beam 5 and as the process of weaving to be described progresses, become woven fabric 20 indicated at 8, Fig. 3.

Between the two beams, the warp 7 is stretched over transverse lease bars 9 and 10, the bar 9 being conveniently supported by a pair of studs 11—11 on the side rails 3 and 4 projected through 25 suitable perforations in opposite ends of the bar 9, and the bar 10 being supported by downwardly extending arms 12—12 at opposite ends thereof inserted in bores 13 (see Fig. 2) in the side rails.

Means will now be described by which the warp 30 threads 7 stretched between the bars 9 and 10 are shedded and by which, after a shuttle trailing a weft thread is passed therethrough, the latter is beaten up into the fell or edge of the cloth. In the inner face of each of the rails 3 and 4 is provided a groove or guideway 14 and 15 thus providing a pair of parallel grooves to guide the slides 16 and 17. The slides 16 and 17 are connected by three transversely extending rods 18, 19 and 20. The ends of the rods may be driven into bores 40 in the guides 16 and 17 to rigidly connect them so that the guides and the rods may move back and forth as a unit.

A pair of uprights 21—21 extend upwardly from the rods 18 and 19 near each end thereof and are 45 connected together near the upper ends by bridging members 22—22 and the bridging members 22 and the uprights 21 may be and preferably are integral. Upon the bridging members 22 is mounted a finger rest 23 which may be made of 50 wood or other suitable material. Each pair of uprights 21—21 may be joined by a tie 24. The uprights 21 and bridging members 22 are thus connected rigidly to the slides 16 and 17 and the slides may be reciprocated by push or pull forces 55 applied or transmitted to the uprights 21.

Upon opposite end portions of the bar 20 are oscillatably mounted bell crank elements 25—25 comprising arms 26 and 27 on substantially opposite sides of the bar 20. A weight bar 28 is connected at opposite ends to the bell crank arms 26—26. A frame indicated generally at 29 is supported upon the bell crank arms 25, the frame comprising a horizontal bar 30 oscillatably supported in the ends of the arms 25 and having uprights 31—31 extending upwardly from the bar 30 and rigidly connected at their upper ends to a hand bar 32. The opposite uprights 31 are also rigidly connected together by a reed support 33, the hand bar 32 and reed support 33, preferably 65 being made from wood or like material. Arms rigidly connected to the uprights 31—31 have at their free ends grooved wheels 35 thereon disposed between the above described uprights 21—21 and adapted to slide or roll vertically there- 70 between.

The parts just described are so made and proportioned that normally they will take up the position illustrated in Fig. 1, in which the weight bar 28 has rocked around until it is in substantially a horizontal plane with the rod 20 on which the bell crank oscillates and in this position it balances the weight of the bar 30, uprights 33, hand bar 32, arms 34 and wheels 35 and other parts associated therewith to be described.

To insure that the frame 29 comprising the 10 above listed parts occupies the predetermined desired position which will become clear hereinafter, the effectiveness of the weight bar 28 may be adjustably varied by means of supplemental weights 36—36, best shown in Figs. 6 and 8, which may be 15 attached to the weight bar 28 by bolts 37—37.

Mounted upon the frame 29 and movable therewith is a lease reed construction indicated generally at 38 and shown separately in Figs. 9 and 10. The lease reed, Figs. 9 and 10, comprises 20 a plurality of reed elements 39—39 preferably formed from sheet metal strips perforated at their opposite ends and in their intermediate portions provided with elongated perforations or eyes 40—40. The metal surrounding the eyes 40 is 25 twisted out of the plane of the reed elements so that when the reed elements are disposed edgewise as shown in Fig. 10, the eyes will be open in the edgewise direction. The reed elements are spaced apart by rubber or like preferably compressible 30 washers 41, and bolts or rivets 42 having heads 43 on their opposite ends are inserted through the washers 41 and through the above-mentioned perforations in the reed elements, clearly shown in the lower part of Fig. 10; and the reed elements 39 are thus all mounted upon the rivets or bolts 42 as a complete assembled unit in predetermined spaced relation from each other. Any suitable number of the reed elements 39 may thus be assembled into the lease reed unit 38, there being 40 half as many reed elements as there are warp threads on the loom.

The reed support 33 above described has a groove 44 in the upper side thereof, and the hand bar 32 has an open sided groove 45 therein. The grooves 44 and 45 are spaced apart to admit therein the lease reed unit 38, the unit being first placed in the lower groove 44 and then rocked inwardly into the groove 45. The hand bar 32 is preferably made in two parts 32 and 32a hinged together as 50 at 46 and the part 32a may be hingingly moved around to the position illustrated in Fig. 1 to clamp the upper portion of the lease reed unit in the groove 45. When it is so clamped, the rubber washers 41—41 may be compressed against adjacent wall portions of the notch and groove to render secure the engagement of the lease reed unit with the reed support 33 and hand bar 32. 55

To hold the hand bar part 32a in clamping position as referred to, a pair of clip devices 47 is provided, each rotatable around a screw 48 and comprising opposite fingers 49 which may be rotated from the position illustrated in Fig. 9 to that illustrated in Figs. 1 and 6, for example, to hold the hand bar portions 32 and 32a in the lease reed clamping position referred to; and the devices 47 may have bent-up portions 50, best shown in Fig. 6, by which they may be twisted to release the clamping action for removal of the lease reed unit.

When the warp threads on the warp beam 6 are, in setting up the loom for work, passed over to and upon the cloth beam 5, alternate threads are passed between adjacent reed elements 39 as shown at 51—51, Fig. 10; and the 75

other alternate threads are passed through the eyes 40 as shown at 52—52.

The means for drawing the warp threads tight on the cloth beam will be described hereafter.

As will be apparent, if the lease reed construction 38 is raised, for example to the position shown in Fig. 5, the warp threads 52 in the eyes 40 will be raised above the warp threads 51, forming a shed for the shuttle (which, as in well known practice, is thrown transversely of the warp through the shed); and if the lease reed 38 is lowered, for example to the position shown in Fig. 7, the shed will be formed with the threads 52 below the threads 51. The parts are preferably so arranged that when the frame 29 as a whole is in its normal position counterbalanced by the weight 28 as shown in Fig. 1, there will be a small depth of shed as shown at 53.

The operations of shedding and beating will now be described. To form a shed for the shuttle, as shown in Fig. 5, the operator may place the thumb of one hand as shown at 54 under the edge of the hand bar 32 and place the fingers of the hand as shown at 55 upon the finger rest 23. By pulling upward on the hand bar 32, the entire frame 29 will move upwardly, the wheels 35—35 rolling or sliding between the uprights 21—21 and at the lower end of the frame 29 the bar 30 will oscillate the bell crank 25 around the bar 26, thus rotating the weight 28 counterclockwise as viewed in Fig. 5. A pair of stops 56 are provided preferably in the form of fingers extending below the bar 19 and the weight 28 (or the weights 36 if such weights are used) will engage the stop 56 and be stopped thereon.

The parts referred to and as hereinbefore described, provide a toggle arrangement, including the arm 28 of the bell crank 25 and the side frame members 31. The downward thrust of the now stretched warp threads 52 pushing downwardly on the reed unit 38 exerts a downward thrust at the pivot connection 57 of the frame and bell crank 25, and if the bell crank 25 be rotated by the above described lifting operation so that the pivot connection 57 lies to the left of a line drawn from the eye 40 to the bar 28, this thrust will tend to rock the bell crank counter-clockwise, and inasmuch as the bell crank is stopped upon the stop 56, and cannot rotate, the frame 29 is thereby locked in its position shown in Fig. 5 with the warp threads shedded. The inertia of the weight 28 (or 28 and 36 if the weights 36 are used) will, following a quick upward thrust by the thumb 54, easily carry the bell crank 25 to the toggle locking position illustrated and described above.

The shed now being formed, a shuttle may be thrown therethrough in the usual manner, and this being so well understood in this art, is not illustrated. When the shuttle has been thrown and the weft thread lies in the shed, the beating operation is performed by the operator, moving his fingers 55 from the finger rest 23 and gripping the hand bar 32 and pulling thereon in the direction away from the finger rest 23, that is, toward the cloth beam. This movement will first break the above described toggle by rotating the bell crank 25 clockwise as viewed in Fig. 5. The frame 29 will then drop, partly by gravity and partly by the force of the stretched warp threads 52, to the normal position illustrated in Fig. 1 at which the warp threads are slightly shedded; and by a continuation, uninterrupted, of this same movement of the hand, the operator draws the hand bar 32 towards the cloth beam, toward

the left as viewed in Figs. 1 and 5, and the reed elements 39 of the lease reed unit 38 will themselves perform the beating operation at the fell which is, as will be understood, located approximately at the point 97 in Fig. 1.

By providing the small shed 53 referred to, the warp threads will not tend to intermingle and prevent a clean beating operation.

As is well known in loom operations, the shed must next be made in the opposite direction, that is to say, in the direction indicated in Fig. 7. To this end, the operator first pushes backward on the hand bar 32, moving it to the position of Fig. 1, and restoring again the small bridge 53 to again clearly separate the warp threads. Then, by means of his thumb as shown at 54 in Fig. 7, the operator presses downwardly on the hand bar 32 and this operation may be assisted if desired by slightly hooking the fingers of the hand as shown at 55, Fig. 7, under the finger rest 23. This operation moves the parts from the position of Fig. 1 to that of Fig. 7, the wheels 35 moving vertically between the bars 21—21, and the bell crank 25 being rotated clockwise around the bar 26. In this movement, the weight 28 by its inertia will carry the pivot connection 57 around clockwise until the bar 28 on which the bell crank oscillates is to the right of a line drawn between the pivot connection 57 and the eye 40 in which the warp threads 52 are disposed, the warp threads now exerting an upward thrust on the frame 29 and holding the toggle locked in the position illustrated, holding the shed formed in the lower position illustrated. And again this operation may be performed by a quick downward thrust on the hand bar 32.

The shuttle may now again be thrown through the shed and immediately thereafter the fingers at 55 may be removed from the finger rest 23 and inserted behind the hand bar 32 and by simply pulling thereon, the toggle will be broken and by a continuation of the same movement the beating operation will again be performed.

As above referred to, the inertia of the weight 28 will assist completion of the toggle locking movement of the mechanism, but this is not essential and the mechanism as illustrated will move and effect a toggle lock in each direction whether the movement is slow or fast. As shown in Fig. 7, the movement of the mechanism in forming the shed may definitely be stopped by engagement of the weight 28 with the lower part of the reed assembly 38, or, if preferred, upon an adjacent part of the reed support 33; so that the motion in either shedding direction is positively stopped at a predetermined amount of shed so that the operation is uniform.

As will be seen by the foregoing, the shedding and beating operations may be performed with one hand and that the shed is formed in either direction by a simple vertical movement and the beating is effected after each shed by a simple horizontal pull movement.

Referring now to the construction of the beams, the warp beam is shown in Figs. 1, 2 and 4. The beam 6 comprises a pair of inner spindle elements 58 and 59, coaxially aligned and provided at their outer ends with tongues 60 and 61 which are normally disposed in recesses 62 in the side rails 3 and 4 to hold them against rotation. Between the inner ends of the spindle portions 58 and 59 is a fixed disc or a cylinder 63 of rubber or other compressible expandable material. A bolt 64 extends preferably axially through the tongues 60 and 61 and through the spindle ele-

ments 58 and 59 and the rubber cylinder 63, and is secured to the spindle element 58 by a transverse pin extending through the bolt and spindle elements, and has a head or nut 65 at one end and a wing nut 66 at the other end, whereby upon rotating the wing nut the rubber disc 63 may be compressed or allowed to expand axially.

Telescoped over the spindle elements 58 and 59 and the rubber cylinder 63 is a tubular body 67 of a spool indicated generally at 68 having spool heads 69—69 secured thereto. The warp threads 7 referred to hereinbefore are wound or wrapped on the spool 68.

In the normal operation of the loom, a wing nut 66 is turned to compress the rubber cylinder 63 and expand it outwardly radially to engage the inner wall of the tubular body 67 of the spool 68 to thereby rigidly connect the spool to the spindle elements. The spindle elements are connected against rotation to the side rails 3 and 4 as above described so that the spool is prevented from rotating. The warp may now be stretched and the weaving operation be performed, and when it is desired to take up the work on the cloth beam to be described, the wing nut 66 may be loosened which will permit the spool 68 to turn on the rubber cylinder 63, and after again tightening the wing nut 66, the warp may be again stretched.

30 The construction just described permits of removal of the spool 68, and to this end the wing nut 66 may be loosened and the spool 68 turned to loosen the warp whereupon the tongues 60 and 61 may be withdrawn from the recesses 62—62 35 and the spool may then be telescoped endwise off of the spindle elements. The purpose of this construction will be referred to later.

The construction of the cloth beam is illustrated in Figs. 1, 2 and 3. The cloth beam 5 comprises a pair of spindle elements 70 and 71 and a rubber cylinder 72 therebetween. The spindle element 71 is rotatably supported in a bore 73 in the frame side rail 3, having a bearing portion 74 of reduced diameter for that purpose. The spindle element 70 likewise has a reduced diameter portion 75 which is rotatably supported in a C-form recess 76 in the rail 4. The cloth beam is normally held by the tension of the web in the direction to keep the neck 75 from coming out of the recess 76; but to prevent accidental removal thereof when there is no tension on the warp, a pin 77 is provided vertically slidable in a pocket 78 in the rail and held in the position projecting out of the pocket by a spring 79. Upon depressing 55 the pin against the spring tension, the neck 75 is released and may be removed from the recess for a purpose to be described.

A ratchet wheel 80 is secured to the spindle element 70 outwardly of the rail 4, the wheel serving 60 also as a hand wheel for rotating the cloth beam 5 and for this purpose finger holes 81 may be provided therein. A ratchet pawl 82 engages the teeth of the ratchet wheel 80, being spring-pressed thereagainst by a spring 83, the ratchet 65 being formed so that the hand wheel 80 may be rotated clockwise as viewed in Fig. 2 and is prevented thereby from rotating counterclockwise; but to permit the wheel to be rotated counterclockwise, the pawl 82 may be depressed by the 70 thumb or finger engaging the portion thereof which projects above the base 2 as clearly illustrated in Figs. 2 and 3.

The ratchet wheel 80 is preferably removably secured upon the spindle element 5 and to this 75 end the neck 75 outwardly of the recess 76 is

provided with a tongue 84 which projects through a correspondingly shaped perforation 85 in the wheel, shoulders 86 being provided at the sides of the tongue. A bolt 87 extends axially through the spindle elements 70 and 71 and through the neck 75 and tongue 84, and is threaded at one end into a nut 88 and is secured to the spindle element 70 by a transverse pin extending through the bolt and spindle elements. The nut 88 may be rotated to align it with the perforation 85 in the wheel and the wheel may then be withdrawn over the nut, or, with the wheel in position on the neck 84, the nut may be turned to overlap the wheel at the edges of the perforation 85 to clamp it against the shoulders 86. In the preferred construction, the nut 88 is made of wood or like material and a metal nut 89 is embedded therein.

The opposite end of the bolt 87 extends outwardly through the neck 75 and has a wing nut 90 thereon. A tube 91 is telescoped over the aligned spindle elements 70 and 71 and rubber cylinder 72 and has, at the beginning of the weaving operation, the warp wound thereon and as the work proceeds has the cloth indicated at 92 wound thereon. In the normal operation of the loom, the work or cloth is kept wound up to keep the warp tight by means of the ratchet hand wheel 80 and the tube 91 is rigidly connected to the spindle element so as to draw upon the warp by the expansion of the rubber cylinder 30 72 into frictional engagement with its inner wall by the wing nut 90 in a manner more fully described in connection with the other beam and Fig. 4.

35 The tube 91, however, may be removed from the beam by depressing the pawl 82 to relieve the tension of the warp, and then after turning the beam to give slack in the warp, the neck 75 may be drawn out of the recess 76 by first depressing the pin 77 and then the neck 75 may 40 be drawn longitudinally out of the bearing 73; then, after loosening the grip upon the tube 94 by loosening the wing nut 90, the tube and the work thereon may be telescoped off of the spindle elements 70 and 71.

45 By the warp beam and cloth beam constructions above described, the warp may at any time be loosened at the warp beam and taken up, as the work progresses, at the cloth beam, and the warp at all times maintained tight between the beams for the weaving operation above described.

As described in connection with Figs. 9 and 10, the lease reed structure 38 may be mounted in the shedding frame 29 or removed therefrom as 55 a unit. It has also been described above how the warp beam spool 68 and the cloth beam tube 91 may be removed from their supports by telescopically sliding them off of the spindles which support them. It will therefore be clear 60 that the warp supply and the cloth or work whether finished or not and the warp thereon and the lease reed 38 may be removed as an assembled unit and maintained intact, the lease reed 38 being retained on the warp threads by 65 the fact that alternate threads are embraced by the eyes 40. Such an assembled unit is illustrated in Figs. 11 and 12, the view being somewhat diagrammatic and drawn to a smaller scale. By this means, one of the important advantages 70 of my invention may be enjoyed, which will now be described.

I may provide "refill" units in great numbers and therefore cheaply, each consisting of the warp spool 68, cloth tube 91, warp 7 thereon 75

and reed unit 38 on the warp. These may be provided in various widths and colors of warp. The operator of a loom such as that described above may quickly and conveniently put this 5 unit into the loom by simply telescoping the tube and spool on their respective spindles and mounting the reed units 38 on the frame 29 as above described. In this connection it will be observed that if the warp spool is first mounted in position, the cloth tube and the reed construction 10 may thereafter be projected through the frame 29, the vertical and horizontal space between the hand bar 32 and reed support 33 being made sufficient for this purpose, as illustrated.

15 Similarly, if after a piece of work has been started but not completed, and it be desired to change over to another piece of work, the unfinished work may be removed from the loom by telescoping the spool and tube off from their spindles and removing the reed unit from its 20 mounting and then removing the spool, tube, warp and reed from the loom, laying them aside for further use at a later time and substituting new work therefor.

25 By this means the tedious operation which has been heretofore necessary of stringing or laying the warp threads through the eyes of the reeds or heddles and winding them smoothly and with uniform tension upon the cloth beam are all un- 30 necessary so far as the operator of the loom is concerned, these operations all being performed by the manufacturer when the said refill unit is made.

As illustrated and described hereinbefore, the 35 cloth beam removable element is in the form of a tube and the warp removable element in the form of a spool. It will be understood that this difference in these elements is not necessary and that both of them can be tubes. This 40 is illustrated in Figs. 16 and 17 in which a tube 95 and a tube 96, identical therewith, as preferred, are shown, together with the lease reed 38 and warp thread 7 threaded through the reed and wound on the tubes. For most work with these 45 refill units, a relatively thin layer of warp thread 7 will be necessary to be wound on the tube 96 and the head of the spool 69 shown and described above will be unnecessary. Omitting the head of the spool furthermore renders the two tubes in 50 the lease reed more compact whereby they may be rolled up together into sufficiently small volume to be carried in a lady's hand bag or to be

slipped into a mailing tube. Such close-coupled assembly is illustrated in Figs. 16 and 17 and the means by which such a small-sized refill unit for looms is made possible, is one of the essential features of my invention.

Thus I have provided, in the above described refill unit, a new article of manufacture and a new method of operating looms.

My invention is not limited to the exact details of construction illustrated and described. 10 Many changes and modifications may be made within the spirit of my invention without sacrificing its advantages and within the scope of the appended claims.

I claim:

1. In a loom, a main frame, a rotatable cloth beam comprising spaced cylindrical bearing portions, a bore on the frame for one bearing portion, a recess in the frame for the other bearing portion and means for retaining it in the 20 recess, comprising an obstruction projecting into the recess in front of the corresponding bearing portion and resiliently operably yieldable to remove it from recess obstructing position, the beam being removable from the bearing portions 25 by lateral movement from the recess after manually effected operation of the yieldable obstruction and by subsequent longitudinal movement from the bore.

2. In a loom, a main frame, a warp beam comprising a tubular portion rotatable on the frame, means to optionally non-rotatively secure the tubular portion to the beam, tongue portions at opposite ends of the beam, recesses in the frame for receiving the tongues, warp on the tubular 35 portion, means for tensioning and untensioning the warp, the tongues being adapted to be normally held in the recesses solely by the tension of the warp, and the beam being freely removable from the frame by removing the tongues 40 from the recesses after untensioning of the warp.

3. A loom as described in claim 2 and in which the securing means is carried by the beam and operable externally thereof.

4. A warp refill unit for hand operated textile 45 looms comprising a pair of tubes adapted to be telescoped over the warp and cloth beams respectively of the loom, warp wound on both tubes, and a reed element intermeshed with the warp between the said tubes and adapted to be detachably secured to the loom shedding mechanism.

DAVID C. CHURCHILL.
